UNITED STATES PATENT OFFICE.

EDWARD H. AMET, OF WAUKEGAN, ASSIGNOR TO CHARLES DICKINSON, OF CHICAGO, ILLINOIS.

APPARATUS FOR REPRODUCING PHONOGrams.

SPECIFICATION forming part of Letters Patent No. 539,212, dated May 14, 1895.

Application filed January 9, 1895. Serial No. 534,320. (No model.)

To all whom it may concern:

Be it known that I, EDWARD H. AMET, a citizen of the United States, residing in Waukegan, in the county of Lake and State of Illinois, have invented a new and useful Improvement in Apparatus for Reproducing Phonograms, of which the following is a specification.

My invention relates to the copying or reproduction of phonograms or sound writings.

10 My invention consists in the novel construction of parts and devices and novel combinations of parts and devices herein shown and described and specified in the claims.

15 In the accompanying drawings, forming a part of this specification, Figure 1 is a plan view of an apparatus suitable for use in practicing my invention and embodying the machine or apparatus features of my invention. Fig. 2 is an enlarged vertical cross-section 20 taken on line 2 2 of Fig. 1, and Fig. 3 shows a modification.

25 In the drawings A represents the frame and B and B' the revolving shafts or holders for holding and revolving synchronously the original phonogram cylinder C and the similar cylinder C' upon which the copy is to be made.

30 D is the traveling head, frame or slide, upon which the reproducing or following stylus F and the recording or engraving stylus H are mounted. The reproducing stylus F is, or should be, of the usual round pointed jewel-form, and it is secured to a two-way, thin, light flexible spring f, preferably of steel. 35 This spring f is made two-way for the purpose of giving the stylus F the necessary freedom of movement laterally to follow the lines of writing on the cylinder C and also the necessary freedom of movement up and down to 40 follow the elevations and depressions of the sound writing on said cylinder. The spring f can be most conveniently made flexible in two directions by simply giving it a twist f'. By making the spring arm f thus capable of 45 yielding in two directions I obviate the necessity and expense of pivotally mounting said arm upon its support d.

To give opportunity for easily adjusting the direction and position of the reproducing 50 stylus F in relation to the cylinder C I preferably provide the spring arm f with an ex-

tension f² of copper or other pliable and little resilient material. This makes a means for adjustment of the position and direction of the stylus, which is not only lighter and 55 cheaper but more convenient than adjusting screws or other means.

The recording or engraving stylus H is preferably of the usual sharp pointed jewel construction familiar to those skilled in the art, 60 and it is carried by a lever h which is pivoted at h' to a weight or weighted arm h², which itself is pivoted at h³ to the head D. At the free end of the weighted arm h² is an adjustable stop h⁴ to limit the movement of the weighted 65 arm. The end of the lever h opposite to the stylus H is connected by a flexible link h⁵ to the stylus F; this being done preferably through an intermediate lever h⁶ pivoted at h⁷ to an arm d⁴ on the head D, and which lever h⁶ 70 is connected by a link h⁸ with the stylus F, or its supporting arm. As shown in Fig. 2 the intermediate lever also serves to multiply the movement, thus tending to make the copy of greater clearness and volume than the original. In the modification shown at Fig. 3 the intermediate lever h⁶ is omitted and the link connection made direct between the arm of the reproducing stylus and the lever or arm carrying the recording stylus. 75

80 The link connection between the reproducing stylus and the recording stylus, whether the same be made in one piece, as indicated in Fig. 3, or in two pieces h⁵ h⁸, as indicated in Fig. 2, is preferably made, I find, of lead wire, 85 or other substance possessing little elasticity, though it may be made of any suitable material.

The two shafts B and B' are revolved synchronously by a belt b on the pulleys b' b². 90 The traveling head, slide or frame D is fed or reciprocated by a feeding screw b³ on the shaft B engaging a screw threaded arm or nut d⁵ secured to the head D.

95 It will be observed that the end of the recording stylus lever h to which the link h⁶ is connected, moves directly in unison with the reproducing stylus F, while the recording stylus H on the opposite end of this lever moves reversely in unison with the reproducing stylus F; so that a depression on the cylinder C forms a corresponding depression on 100

the cylinder C', and in like manner an elevation on the cylinder C forms a corresponding elevation on the cylinder C'; thus making the cylinder C' a direct instead of a reverse copy of the cylinder C, and, as the connection between the reproducing stylus F and the recording stylus H is direct or mechanical, without the intervention of vibrating diaphragms or sound waves in the air, the copy C' is necessarily an exact and perfect copy of the original C.

The spring arm f serves to hold the reproducing stylus F properly in contact with the original phonogram cylinder C, and the weighted arm h² serves to keep the recording stylus H properly in contact with its cylinder and the link connection between the two styli taut or under tension, so that the movement of the stylus F is properly communicated to the stylus H.

I claim—

1. The combination with revolving shafts B B' for holding and revolving the cylinders C C', of a traveling head D, reproducing stylus F secured to a spring arm, recording stylus H secured at one end of a lever h, said lever h, a weighted arm h² to which said lever h is pivoted, and a link connection between the opposite end of said lever h and said reproducing stylus, said reproducing stylus carrying spring arm f, being a spring flexible in two directions, substantially as specified.
2. The combination with revolving shafts B B' for holding and revolving the cylinders C C', of a traveling head D, reproducing stylus F secured to a spring arm, recording stylus H secured at one end of a lever h, said lever h, a weighted arm h² to which said lever h is pivoted, and a link connection between the opposite end of said lever h and said reproducing stylus, said reproducing stylus carry-

ing spring arm f having an extension f² of flexible, non-resilient material, substantially as specified.

3. The combination with revolving shafts B B' for holding and revolving the cylinders C C', of a traveling head D, reproducing stylus F secured to a spring arm, recording stylus H secured at one end of a lever h, said lever h, a weighted arm h² to which said lever h is pivoted, and a link connection between the opposite end of said lever h and said reproducing stylus, and an intermediate lever h³ inserted in the connection between said lever h and said stylus F, substantially as specified.

4. In a phonogram reproducing or copying mechanism, the combination with a reproducing stylus mounted on a spring arm, of a recording stylus mounted on a weighted arm, and a connection between said spring arm and said weighted arm, said connection being provided with a lever for multiplying the movement, substantially as specified.

5. In a phonogram reproducing or copying mechanism, the combination with a reproducing stylus mounted on a two-way spring arm, of a recording stylus mounted on a weighted lever and a connection between said lever and said spring arm, substantially as specified.

6. In a phonogram reproducing or copying mechanism, the combination with a reproducing stylus mounted on a spring arm, of a recording stylus mounted on a weighted arm, and a lead wire connection between said spring arm and said weighted arm, substantially as specified.

EDWARD H. AMET.
